WINDOW SASH

Ellis E. Donahoe, Dormont, Pa., assignor to The Don-Economy Window Company, Pittsburgh, Pa., a partnership composed of Ellis E. Donahoe, Benjamin M. Clasky, Thomas H. McGregor, and Charles A. Roland

Application March 28, 1939, Serial No. 264,539

3 Claims. (Cl. 20—49)

My invention relates to window structures of that type which is pivotally mounted for rotative movement about an axis parallel to the plane of the window and which may, if desired, be also movable in a direction parallel to said plane.

One object of my invention is to provide an improved sealing arrangement for bridging the spaces between the edges of a rotatable window and the frame in which the same is mounted.

Another object of my invention is to provide a structure of the character referred to wherein the strips which make the seal, serve also as locking strips to normally prevent tilting of the window sash, and will be automatically shifted between their operative and inoperative positions simply through raising and lowering of the window sash.

Still another object of my invention is to provide an improved form of pivotal connection between the swinging sash and stationary parts of the structure, whereby the sash can be yieldably held at desired tilted positions, and wherein the parts of the pivotal connection are snugly held to avoid looseness and play, such parts being nevertheless readily disconnectable in order to permit complete removal of the window sash from its frame.

One form which my invention may take is shown in the accompanying drawing, wherein Figure 1 is a face view partially elevational and partially in section, of a window structure embodying my invention; Fig. 2 is a vertical sectional view through the same; Fig. 3 is an enlarged view taken on the line III—III of Fig. 1; Fig. 4 is a sectional view on an enlarged scale, showing the members whereby a detachable pivoted connection is provided between the window sash and the stationary members of the structure; Fig. 5 is a view taken on the line V—V of Fig. 4; and Fig. 6 is an end view of the structure of Fig. 4.

For convenience of illustration, I have shown a window sash mounted in frames of somewhat the usual form and having rotative movement about a horizontal axis, but it will be understood that the invention is applicable also to a window sash which is mounted for movement about a vertical axis.

The window frame is composed of side-frame members 5 and 6 and a sill member 7. The numeral 8 represents the lower sash, and the numeral 9 a portion of the upper sash which may be constructed and mounted in substantially the same manner as the sash 8, to be hereinafter described. A pane of glass A is secured in the

sash 8 in the usual manner, and guide strips 10 and 11 are secured to the side frame members 5 and 6. Between each pair of guide strips 10 and 11 a sash strip 12 is slidably mounted, as shown more clearly in Fig. 3. These strips 12 may be formed separately from the vertical bars 8a of the sash 8, or will be cut therefrom in case it is desired to apply my invention to a window sash of a standard form. The adjacent portions of the members 8a and 12 are provided with vertical 10 grooves for the reception of a locking and sealing bar 13, the depth of the groove in each of the sash members 8a being substantially equal to the width of its contained bar 13. Each bar 13 is provided with two angular slots 14. A pin 15 extends through each of the angular slots 14 in the bars 13, so that as the bars are raised and lowered, they will be moved outwardly and inwardly with respect to the vertical slots in the sash members 8a. 20

The sash 8 is pivotally connected to the sash strips 12 by means to be hereinafter described, so that when the locking and sealing bars 13 are pushed entirely clear of the slots in the members 12 and into the sash members 8a, the sash 8 25 can readily be tilted, somewhat as shown in Fig. 2, or can be entirely reversed to permit cleaning both sides of the glass, without draft through the room.

When the sash 8 is lowered against the sill 7 30 as shown in Fig. 1, the locking bars 13, which are somewhat longer than the sash, are projected upwardly and outwardly into the vertical slots in the sash strips 12, as shown more clearly in Fig. 3, and at the left-hand side of Fig. 1. The 35 sash 8 is therefore rigidly locked against tilting movement, and the space between the sash members 8a and 12 is sealed to keep out cold air and moisture. The usual ropes and pulleys (not shown) may be attached to the sash strips 12, 40 and the sash member 8 and the strips raised and lowered as a unit.

Since the locking strips 13 can be moved inwardly to their retracted positions within the sash 8 by simply raising the sash 8 until the upper ends of such strips strike the top of the window frame, as the lower ends of the strips 13 will then project below the window so as to be moved again into locking position when the sash is lowered, there is in effect automatic movement 50 of such sealing strips simply through raising and lowering of the window, with the result that no special provision is required for direct manual manipulation of the sealing strips. Even if handle-like projections were provided on the upper 55

ends of the sealing strips for shifting them longitudinally, in many cases this would be a difficult operation, because they often become rusted, bound by grit or warped, whereas the momentum of the window in raising and lowering it will impart sufficiently sharp blows to the ends of the sealing strips to effect shifting movements thereof.

The upper sash 9 may be mounted in substantially the same manner as the sash 8, but the locking strips 16 of such upper sash will preferably have their slots 17 of reversed angularity with respect to the angle of the slots 14 in the strips 13, so that when the upper sash is raised 15 and the locking strips are consequently in their lowermost position, they will be projected into locking position within grooves in sash strips corresponding to the strips 12.

The pivotal connections between the swinging 20 sash and the stationary members comprise a plate 20, set into each of the sash strips 12 and suitably secured thereto by screws; a second plate 21 set into and secured to the sash member 8a, and a shaft 22 that serves as a pivot pin, the shaft 25 having suitable bearing support in the plates 20 and 21. A bushing 23 loosely surrounds the shaft 22 and is provided with a pair of arms 24. A spring 25 is interposed between the bushing 23 and a fixed collar 26 on the shaft 22, so that the bushing 23 is yieldably projected toward the plate 20 and the arms 24 will be yieldably held in radiating grooves 27 on the inner face of the plate 20. The arms 24 lie partially within long 30 slots formed in the plate 21 so that they in effect 35 bridge the plane between the meeting faces of the plates 20 and 21. With the locking strips fully withdrawn into the slots in the sash members 8a, the sash 8 can be tilted on its pivotal supports and will be yieldably held at various positions by 40 reason of the arms 24 extending into the radial slots 27 of the plate 20, the outer faces of the arms 24 being rounded so that they will readily slide out of the grooves 27 when tilting the window sash.

45 During swinging of the sash and movement of the spring-pressed retaining arms 24 from one slot 27 to another, the plates 21 and 20 and the sash members to which they are connected will not be spread apart, because the camming movements imparted to the arms 24 when passing from one slot 27 to another slot 27 will simply result in the arms being pushed slightly outwardly within their plate 21, against the spring 25. It will be seen that the bushing 23 and the arms 24 50 can readily be replaced when they become worn.

55 At its inner end the shaft carries a pin 28 which, when in a vertical position, can pass through a vertical slot 29 in the plate 20, to the rear side of such plate, whereupon turning of the shaft through 90° will move the pin 28 to the position shown in Figs. 4 and 6, at which it will engage notches in a boss on the rear side of the plate 20 and the window sash 8 thereby snugly held in position, by reason of the expansive force of the spring 25. This locking together of the parts will not interfere with the swinging of the sash and its plate 21 relative to the plate 20 and the stationary sash member 12.

A key or bar 30 has an extended stud-like projection that is threaded for engagement with a tapped opening in the outer end of the shaft 22, this key member 30 being inserted only when it is desired to detach the sash from the sash strips 12. At its outer end the member 30 is provided 70 with a knurled head 31 which is tapped to receive

the threaded end of a handle 32, whereby the shaft 22 can be operated in opposition to the spring tension, to connect and disconnect the window more readily than it could be done simply by turning the knurled head 31. It will be seen that when the sash bar has been placed in position and the member 30 removed, there are no projecting parts that invite tampering, or which interfere with operating or cleaning the window.

10 From the foregoing it will be seen that my invention has a further advantage in that the sash can be detached from the frame without the need of removing stop beads and parting beads, for the purpose of renewing sash cord or chains, reglazing, applying weather stripping, etc. Also 15 it can be employed with various types of metal sash structures as well as to wood sash.

I claim as my invention:

1. The combination with a window frame, of a sash structure comprising sash strips slidably supported on the frame and each having a longitudinally-extending groove in its inner surface, a sash member disposed between said strips and having grooves that are normally opposite to the grooves in said strips, means for movably supporting the sash member on said strips, a locking strip supported in each groove of said sash member and movable laterally so that its inner edge will extend into the groove of the adjacent sash strip, the locking strips being of greater length than the sash member, and guide means for effecting movement of the locking strips laterally into the grooves in the sash strips when the sash member is moved into engagement with one end of the said frame and for effecting lateral movement thereof out of the last-named grooves when the sash member is moved into engagement with the other end of the said frame.

2. The combination with a window frame, of a sash structure comprising sash strips slidably supported on the frame and each having a longitudinally-extending groove in its inner surface, a sash disposed between the sash strips and having grooves that are normally opposite the first-named grooves, means for movably supporting the sash member on said strips, a pin extending across each of the grooves in the sash, and a substantially straight locking strip lying within each sash groove and having angular slots whose walls are engaged by one of the pins and so arranged that when the locking strip is moved upward relative to the sash, its outer edge will enter the groove in the adjacent sash strip, and when moved in the opposite direction it will be withdrawn into its groove in the sash to permit movement of the sash independently of the sash strip, the locking strips being of greater length than the length of the sash so that when the sash is lowered against the lower end of the window frame, the outer edges of the locking strips will be projected into the grooves of the sash strips, and when the sash structure is elevated into contact with the upper end of the window frame, the locking strips will be forced into retracted position within the grooves in the sash.

3. The combination with a window frame of upper and lower sash structures each comprising sash strips slidably supported on the frame and each having a longitudinally-extending groove in its inner surface, a sash member disposed between each of the sash strips and having grooves that are normally opposite the grooves in the strips, a pin extending across each of the grooves in the edges of the two sash members, and a locking strip lying within each of the sash grooves

and having an angular slot whose walls are engaged by one of said pins, the slots in the locking strips of the lower sash member being so arranged that when the strips are moved relative to the sash, their outer edges will enter the grooves in the adjacent sash strips, and when moved in the opposite directions they will be withdrawn into the grooves in the sash to permit movement of the sash independently of the sash strips, the locking strips being of greater length than the length of the sash so that when the bottom sash is lowered against the lower end of the window frame, the outer edges of its locking strips will be projected into the grooves of the adjacent sash strips, and when the sash structure is elevated

into contact with the upper end of the window frame, the locking strips will be forced into retracted position within the grooves in the sash, and the angular slots in the locking strips carried by the upper sash member being so arranged and being of such length that when the said sash member is elevated into engagement with the upper end of the window frame, such strips will be forced into locking engagement with the grooves in the adjacent sash strips, and when such upper sash is lowered into engagement with the lower end of the frame, its locking strips will be forced out of the grooves in the adjacent sash strips.

ELLIS E. DONAHOE. 15
